DESIGN FOR A GROUP OF STATUARY.

The Schedule referred to in these Letters Patent and making part of the same.

The group consists of three figures, and is called the School Examination. It represents one of the school committee seated in a chair, and pointing out good naturally to a little girl who is standing beside the school-mistress the mistake she has made on her slate, as fully shown in the accompanying drawings.

Having thus described my invention, what I claim, and desire to secure by Letters Patent is—
